Patented July 23, 1912.

UNITED STATES PATENT OFFICE.

ENOS A. WALL, OF SALT LAKE CITY, UTAH.

ENDLESS-BELT ORE-CONCENTRATOR.

1,033,219.

Specification of Letters Patent. Patented July 23, 1912.

Application filed February 8, 1911, Serial No. 607,328. Renewed September 16, 1911. Serial No. 649,735.

To all whom it may concern:

Be it known that I, ENOS A. WALL, a citizen of the United States, residing at Salt Lake City, in the county of Salt Lake and State of Utah, have invented certain new and useful Improvements in Endless-Belt Ore-Concentrators, of which the following is a specification.

My invention relates to endless belt ore concentrators. As usually constructed these endless concentrators travel upwardly under a feed box which discharges the water and pulp thereon. The objection to endless concentrators which travel upwardly under the feed to discharge the concentrates at the top or head of the machine is that the material concentrated on the surface of the belt by the downwardly flowing water is polluted and again mixed with the unconcentrated pulp flowing from the feed box so that the material discharged at the upper end of the belt contains a large amount of gangue. Various means of applying lateral oscillation to this class of belts have also been employed and concentrating surfaces of all sorts have been used without satisfactory results owing to the upward travel of the belt under the feed box or supply to the point of discharge.

The object of the present invention is to provide an endless ore concentrator which shall travel downwardly in the direction of the flow of water or pulp so that the concentrated material will not be again mixed with the pulp being fed to the belt and will be discharged at the lower end of the belt where the water and gangue are also discharged but without their becoming mixed.

A further object is to impart to such a downwardly traveling endless concentrator a differential longitudinal reciprocatory movement to cause the concentrates to move toward the head.

A further object is to provide such a concentrator with a working surface formed of a series of flat, unrifled, horizontal surfaces in step-like order, the lower or discharge edge of one step being spaced above and projecting over the upper or rear edge of the next step below, and the rear or upper edges of all the steps being secured to the belt and vertical walls or risers being there provided against which the concentrated material will be moved by the bumping or jarring action and said vertically disposed walls or risers constituting supports

for the projecting edges of the overlying steps or planes.

These objects I accomplish by the construction shown in the accompanying drawings in which—

Figure 1 is a side elevation of an endless ore concentrator containing my improvements; Fig. 2 is a detail sectional view; Fig. 3 is a detail plan thereof; Fig. 4 is a detail longitudinal section of a modification.

A designates the foundation to which is hinged the head end of a frame-work B, the tail end of which is adjustable vertically by means of underlying wedges B', provided with adjusting screws B², one only being shown. The upper portion of the frame B is provided with an inclined portion B³, having a series of rollers b, mounted thereon. Upon the rollers b is mounted the inclined reciprocating concentrator frame C, provided at its ends with transverse rollers C', C², mounted in suitable bearings c, c, as shown in Fig. 1. Around the rollers C', C², passes the endless concentrator belt D, with its upper run supported on rollers C³, mounted in bearings c³ on the upper side of the reciprocating frame C. The upper or head end roller C³ is driven by a pulley c' from the belt c².

The concentrating surface of the belt D, is formed by a series of horizontal steps with unobstructed surfaces so that the flow down the steps will be unimpeded by any form of riffles, dams, or recesses. These stepped surfaces are formed by horizontal plates or strips E, of metal, wood, linoleum or other material suitable for the purpose. As shown in Figs. 1, 2, 3, the steps are provided with upturned sides e to retain the material from lateral displacement, and the steps or plates are secured by cross pieces or angle strips E', extending across the upper sides and riveted or otherwise fastened to the belt D, as shown in Fig. 2. The lower end of one step or plate E, rests upon the cross piece or strip E' next below so that while the belt D extends down at an angle the steps will all lie in substantially horizontal planes and the strips or cross pieces E' will form the risers or vertical walls of the steps.

The purpose of this overhang is to provide a protected space or pocket under the discharge edge of every step within which the concentrate will be

forced by the differential reciprocation of the concentrator frame and belt, as the heavier particles of mineral drop by gravity from one step to the other; the water and lighter material falling from one step to the other at points beyond where the heavier concentrates fall. The steps or plates E are somewhat narrower at their forward or discharge edges in order that 10 they may have an easy telescoping fit one within the other.

F designates a frame at the head end of the machine and F' is a bumper post thereon.

15 G designates a vertically extending lever pivoted at its lower end to a horizontal, adjustable screw rod G', mounted in a block g, and provided at opposite sides thereof with nuts g', g', by adjusting which the throw of 20 the lever may be adjusted. From the head end of the table a rod H extends through a slot in the bumper post to the lever G, to which it is pivoted. A spring h is mounted on the rod H, between the bumper post and 25 lever G, and the tension of the spring may be regulated by a nut h'. Between the head end of the concentrator frame C, and the bumper post F', the rod H is provided with a bumper h². The upper end of the lever G 30 is actuated by a rotary cam J.

If desired the steps or plates E may be of the same width and run between side strips K, which will prevent the material from flowing from the sides of the steps, 35 but I prefer the construction shown in Fig. 2. Each plate extends the full width of the belt or about six feet while from front to rear edge the plates are about six inches and the height of the strips E', is about 40 three eighths of an inch.

L, designates a series of curtains of suitable material suspended from rods L', extending over the steps or plates with their ends mounted in upright arms L², secured to 45 the opposite sides of the concentrator frame C. The lower edges of these curtains contact with the upper surface of the flowing stream and so break its surface tension, thereby causing the lightest valuable particles which float on the surface of the 50 water to sink and become deposited with the bottom strata or concentrates.

In operation the frame C is adjusted to incline downwardly from the head or feed 55 end to the tail or discharge end so that the plates E, will lie in substantially horizontal planes and the water and pulp will be discharged from the feed box K, upon the head end of the downwardly traveling series of plates. The cam J, will, through lever G and rod H, move the concentrator frame C, and endless concentrator carried thereby slowly toward the tail end, thus compressing the spring h. As soon as the 60 cam releases the lever G, the spring will

suddenly throw the concentrator upwardly toward the head until the bumper h² strikes post F. The water and pulp will flow down the steps faster than the downward movement of the belt and the water will move the 70 mass gently down over the surfaces of the plates in such manner that the mass will be kept in constant rolling motion and this will cause the mineral contents to settle by specific gravity through the lighter gangue down 75 into contact with the plates whence it will be gently pushed forward by the overlying flowing water and gangue to the end of the plate, when by reason of its superior specific gravity the mineral particles will fall vertically down upon the head end of the next step below and back of the point where the water and lighter material will fall and the bumping action toward the head will carry this heavier mineral matter back toward the head and under the overhang. The concentrates will be held under the overhangs until in the downward travel of the belt the plates reach the tail end and turn down around the lower roller at which 80 point a spray pipe S, is placed to spray the plates and cause the concentrates to be dislodged and drop into a suitable receptacle or chute T. The water and tailings will be discharged beyond the discharge point of the 85 concentrates as shown in Fig. 1 and be carried off by a second chute T'.

Having thus described my invention what I claim is:

1. An ore concentrator comprising, an 100 inclined frame, an endless belt mounted thereon and traveling down toward the tail or lower end of the frame, parallel horizontally disposed plates mounted transversely on the belt in descending step-like order with the lower free edge of one plate or step extending over the riser of the next one below, and down which steps the water and pulp flow in the direction of movement of the belt, means for operating the belt, and means for imparting a differential, longitudinal, reciprocation to the inclined frame to progress the concentrates against the risers of the steps; whereby the concentrates along the risers will be carried to the 110 lower end of the belt by its travel and there discharged from the successive steps in rear of the point of discharge of the flowing water and gangue.

2. An ore concentrator comprising, an inclined frame, an endless belt mounted thereon and traveling down toward the tail or lower end of the frame, parallel horizontally disposed channel plates secured at their head ends to the belt and overlapping at their lower or free ends the next plate below, cross-pieces or risers at the head ends of the plates and over which the discharge edges of the overlying plates project; the plates and risers forming a series of steps 115 120 125 130

descending from the head to the tail and down which the pulp and water flow, means for causing the belt to travel downwardly with the feed water and pulp, a feed supply 5 at the upper end of the belt, and mechanism for imparting a differential, longitudinal reciprocation to the inclined frame to progress the concentrates against the risers of the steps; whereby the concentrates along the 10 risers will be carried to the lower end of

the belt by its travel and there discharged from the successive steps in rear of the point of discharge of the flowing water and gangue.

In testimony whereof I affix my signature 15 in presence of two witnesses.
